Attorney.

UNITED STATES PATENT OFFICE.

JAMES J. MULHALL, OF ALBANY, NEW YORK, ASSIGNOR TO JAMES O'HAGAN, JR., OF SAME PLACE.

RAILWAY-RAIL JOINT.

SPECIFICATION forming part of Letters Patent No. 384,061, dated June 5, 1888.

Application filed September 12, 1887. Serial No. 249,432. (No model.)

To all whom it may concern:

Be it known that I, JAMES J. MULHALL, of the city and county of Albany, in the State of New York, have invented new and useful Improvements in Railway-Rail Joints, of which the following is a specification.

My invention relates to improvements in joints for connecting together the conjoining ends of track-rails for railways; and the object of my invention is to provide a simple and effective device for that purpose. This object I attain by the means illustrated in the accompanying drawings, which are herein referred to and form part of this specification, and in which—

Figure 1 is a perspective view of my rail-joint applied to a track-rail; Fig. 2, a transverse section at the line X-X on Fig. 3; Fig. 3, a longitudinal section at the line Y-Y on Fig. 2; Fig. 4, a plan view of my joint-piece detached from the track-rails, and Fig. 5 an end elevation of a modified form of my joint-piece.

As represented in the drawings, A indicates the track-rails, B my joint-piece, and C a cross-tie on which the rail-joint is located.

The track-rails A shown in the drawings are of the ordinary form of T-rail; but any other preferred form of track-rail may be used. At each end of every length the head a is cut away to form substantially a right-angle depression whose lower edge will be parallel to the lower side of the rail, the length of said cut-away portion being equal to one-half of the length of the head b of the joint-piece, and its depth sufficient to remove the head a and leave the exposed upper edge of the web a' of a uniform thickness with the balance of said web.

The joint-piece B is preferably a steel casting, and it is provided with a head, b, of sufficient length to fill the space formed by removing the heads from the conjoining ends of the track-rails, the upper part of the head b being made to conform to the head a of said track-rails. Pendent from and integral with each side of the head b are side flanges, 1, which are of the same length as said head, and which are spaced apart to form a longitudinal groove 50 that fits snugly over the web a' below the space

formed by removing the heads of the track-rails. The lower part of the side flanges bears upon the lower flanges of the track-rails, and thereby gives great solidity to the joint. From their point of bearing on the lower flanges of the track-rails said side flanges are deflected laterally, as at 2, to fit over the upper faces of the lower flanges of the track-rails, and are extended endwise to about twice the length of the head b, so as to produce a long bearing for the joint-piece at the edges of the lower flange of the track-rails. Starting from the edges of the lower flange of the track-rails, said side flanges are extended laterally to form horizontal flanges 3, which bear upon the cross-tie C, upon which the joint-piece B is secured by means of spikes 4 or other suitable fastenings, and when so secured said joint-piece will securely fasten the conjoining ends of the lengths of track-rail in place.

The cross-tie C is generally of wood, and is of the kind commonly used in the construction of railways.

In the modification shown in Fig. 5 the joint-piece B has on the under side of its horizontal flanges 3 pendent lugs b', which pass through mortises made for that purpose in the cross-tie C. Each of said lugs is provided with a transverse mortise, 5, through which keys 6 are driven to bear against the under side of the cross-tie C, so as to secure the joint-piece B in place.

I am aware that rail-joints have heretofore been made with heads to fill the space formed by cutting away the heads of the conjoining ends of the track-rails, the said joints being provided with pendent flanges, some of which were expanded endwise and others laterally, but not in both directions; but these earlier joints have been provided with transverse keys or fastening-plates under the conjoining ends of the track-rails. I do not claim such constructions; but

I claim as my invention—

In a railway-rail joint, the combination of the track-rails having the heads of their conjoining ends cut away, as herein shown and described, and a joint-piece for fastening the ends of said track-rails, said joint-piece comprising a head which fills the space formed

by cutting away the conjoining ends of the track-rails, side flanges pendent from said head and of a uniform length with said head until they bear upon the lower flange of the 5 track-rails, and then expanding both endwise and laterally to form horizontal flanges which bear upon the cross-tie, and by which the joint- piece is secured in place, as and for the purpose herein specified.

JAMES J. MULHALL.
